TWIRLING BATON

Donald L. Sartell, 328 Seminole Road, Janesville, Wis.

Filed Sept. 26, 1963, Ser. No. 76,743

Term of patent 14 years

(Cl. D34—5)

FIG. 1 is a perspective view of a twirling baton embodying my new design.

FIG. 2 is a side elevation of the same disposed vertically, and at an enlarged scale.

FIG. 3 is an end view of the same taken from above FIG. 2.

FIG. 4 is a view looking up from the midpoint of FIG. 2, with the broken line portion of FIG. 2 omitted for convenience of illustration.

FIG. 5 is an end view looking up from the bottom of FIG. 2.

FIG. 6 is a view looking down from the midpoint of FIG. 2, with the broken line portion of FIG. 2 omitted for convenience of illustration.

In FIGS. 1 and 2 a portion is broken away intermediate the ends to show indeterminate length of the baton.

The essential features of my design reside in a baton characterized by balls having a slightly convex end surface terminating in a relatively abrupt radially outermost

circumferential edge, and with a conical band of contrasting material encircling the ball proximate to where it meets a baton shaft, all as shown.

I claim:

The ornamental design for a twirling baton, as shown and described.
